UNITED STATES PATENT OFFICE.

MYRA F. POWELL, OF MOTLEY, MINNESOTA.

DESIGN FOR A PIN.

53,209.

Specification for Design. Patented Apr. 15, 1919.

Application filed January 3, 1919 Serial No. 289,537. Term of patent 3½ years.

To all whom it may concern:

Be it known that I, MYRA F. POWELL, a citizen of the United States, residing at Motley, in the county of Morrison, State of Minnesota, have invented a certain new, original, and ornamental Design for a Pin, of which the following is a specification, reference being had to the accompanying drawing, forming a part thereof.

In Figure 1 of the drawing I have illustrated a perspective view of a design for pin, and in Fig. 2 an edge view.

I claim:

The ornamental design for a pin, as shown.

In testimony whereof I hereunto affix my signature in the presence of two witnesses.

MYRA F. POWELL.
